US00D852198S

(12) **United States Design Patent** (10) **Patent No.:** **US D852,198 S**
(45) **Date of Patent:** **** Jun. 25, 2019**

(54) **ELECTRONIC DEVICE COVER**

(71) Applicant: **Amazon Technologies, Inc.**, Seattle, WA (US)

(72) Inventors: **Jesse Wheeler Moore**, Oakland, CA (US); **Robert Brian Curtis**, San Francisco, CA (US); **Monica Liane Mecchella**, San Francisco, CA (US); **Timothy Eli Wall**, Sausalito, CA (US)

(73) Assignee: **Amazon Technologies, Inc.**, Seattle, WA (US)

(**) Term: **15 Years**

(21) Appl. No.: **29/658,966**

(22) Filed: **Aug. 3, 2018**

Related U.S. Application Data

(62) Division of application No. 29/598,552, filed on Mar. 27, 2017, now Pat. No. Des. 828,360.

CLAIM

The ornamental design for an electronic device cover, as shown and described.

DESCRIPTION

FIG. 1 is a back perspective view of an electronic device cover;

FIG. 2 is a front perspective view thereof;

FIG. 3 is a front view thereof;

FIG. 4 is a back view thereof;

FIG. 5 is a right-side view thereof;

FIG. 6 is a left-side view thereof;

FIG. 7 is a bottom view thereof;

FIG. 8 is a top view thereof;

FIG. 9 is a first opened state view thereof. The first opened state view shows the outer surface of the electronic device cover in an unfolded state; and,

FIG. 10 is a second opened state view thereof. The second opened state view shows the inner surface of the electronic device cover in an unfolded state.

The dashed broken lines depict portions of the electronic device cover which form no part of the claimed design.

1 Claim, 8 Drawing Sheets
